UNITED STATES PATENT OFFICE.

WILLIAM M. FINKENAUER, OF NEW YORK, N. Y.

DESIGN FOR A CASING FOR A RADIO RECEIVING SET.

Application filed September 22, 1922. Serial No. 3,792. Term of patent 14 years.

To all whom it may concern:

Be it known that I, WILLIAM M. FINKENAUER, a citizen of the United States, and resident of New York, in the county of Richmond and State of New York, have invented a new, original, and ornamental Design for Casings for Radio Receiving Sets, of which the following is a specification, reference being had to the accompanying drawings, forming part hereof.

Fig. 1 is a front elevation.

Fig. 2 is a side elevation, and

Fig. 3 is a top plan view.

I claim:

The ornamental design for a casing for a radio receiving set, as shown.

WILLIAM M. FINKENAUER.
